UNITED STATES PATENT OFFICE.

WILLIAM J. SHEETZ, OF WASHINGTON, DISTRICT OF COLUMBIA, ASSIGNOR
OF ONE-HALF TO HENRY M. BAKER, OF WASHINGTON, DISTRICT OF
COLUMBIA.

HOT-WATER HEATING SYSTEM.

No. 812,889.

Specification of Letters Patent.

Patented Feb. 20, 1906.

Application filed March 15, 1904. Serial No. 198,314.

To all whom it may concern:

Be it known that I, WILLIAM J. SHEETZ, a citizen of the United States, residing at Washington, in the District of Columbia, have invented certain new and useful Improvements in Hot-Water Heating Systems; and I do declare the following to be a full, clear, and exact description of the invention, such as will enable others skilled in the art to which it appertains to make and use the same.

This invention relates to hot-water heating systems; and it has for its object to provide a simple, durable, and comparatively inexpensive heating system adapted for the use of gas as a fuel, to provide means for automatically supplying cold water to the boiler to replace waste therefrom, and to automatically reduce or completely cut off the flow of gas to the burner when the water becomes unduly heated; and it consists in the parts and combinations of parts hereinafter described and claimed.

In the accompanying drawings, forming a part of this specification, Figure 1 is a side elevation of my improved heating system; Fig. 2, an enlarged vertical section through the casing of the boiler, showing the water-tubes in side elevation; Fig. 3, a plan view of the boiler with the dome removed; Fig. 4, an enlarged detail view of the thermostat with one-half of its casing removed; Fig. 5, a detail side elevation of the valve mechanism for controlling the water-supply to the boiler, and Fig. 6 a detail side elevation of the head or washer for the thermostat-rod.

Similar letters refer to similar parts throughout all the views.

Referring to the drawings, A represents the foundation or base of the boiler, which consists of a casting, preferably circular in shape, having a series of perforations *a* therethrough for the admission of air to support combustion and also having a peep-hole *b*. Within the casting A the burner *c* (indicated by dotted lines, Fig. 2) is arranged and is supplied with gas by a pipe *d*, which leads to a source of supply, which pipe also supplies a pipe *e*, which leads to a pilot-burner *f*. (Shown by dotted lines, Fig. 2.)

Suitably supported in any desired manner from the base A is a boiler B, which consists of a series of spirally-arranged coils, preferably five or more, of cold-drawn seamless tub-

ing. The tubes are arranged spirally, and the coils gradually decrease in diameter toward the top, so as to form truncated cones, and, as shown, Figs. 2 and 3, are arranged one over the other or in nested form and are staggered, so that the second coil of the series breaks joint with the first or outside coil, the third coil breaking joint with the second coil, the fourth coil with the third, and the fifth coil with the fourth coil; but none of the coils are in contact, so that the products of combustion passing up from the burner pursue a tortuous course around and between the convolutions of the different coils to reach the stack. At their lower ends each coil enters the drum or manifold C and terminates or opens in a similar drum or manifold D at the top, the drum D being of a size sufficient to fully close the space at the top of the innermost coil. Surrounding the coils of tube is a fire-brick jacket E, preferably made in two parts and of truncated form, on which rests a metal dome E', to which is connected the smoke-stack F. The jacket E is inclosed by a sheet-metal jacket F', and the parts are held in position and together by the rods *g*, which connect the perforated ears *h* on the dome and the base of the boiler.

From the manifold or drum D a pipe G leads to a thermostat H, arranged in the main pipe H', which conducts the hot water to the radiator I. The thermostat comprises a short cylinder *i*, having an elbow-coupling *i'* at one end for the end of pipe G and a stuffing-box *i*², through which the rod J works. The end of the rod J which enters the cylinder *i* carries a perforated disk or head *j*, against which a coil-spring K bears, and at its other end is provided with a cap or headed nut *j'*. The spring K is made of a different metal from the metal of which the cylinder is made, so that their expansive qualities vary in degree. A coupling *j*² is provided at the end of the cylinder for connection with the main hot-water pipe H', and a longitudinally centrally-divided casing *j*³ incloses the thermostat, so as to prevent unauthorized meddling therewith. The headed nut *j'* abuts against a valve-rod *k*, which is movably supported in bearings or lugs *k'* and at one end carries a valve *k*². A seat *k*³ is formed in a casing *k*⁴ for the valve *k*², and the pipe L, which leads from the gas-main, is screwed

- into the end of said casing k^4 , and the pipe d connects said casing with the burner c . A light coiled spring k^5 surrounds the valve-rod k and bears at one end against a collar k^6 , secured to the rod k , and at its other end against one of the lugs k' , so that any longitudinal movement of said rod caused by the expansion of spring K is resisted by the spring k^5 , and the latter also serves to return the rod to its normal position when the spring K contracts. The normal position of valve k^2 is open, so as to permit of a free passage of gas therethrough; but when the water is heated to a degree which will cause expansion of the cylinder i and spring K the nut γ' forces or moves the rod k against the resistance of spring k^5 , and thus wholly closes the valve, so as to cut off the supply of gas, or reduces the valve-opening, so as to reduce the supply until the water is cooled off and the spring k contracts, and thus permits the rod k to be returned to its normal position, and thus open the valve k^2 and permit a full or increased flow of gas therethrough. At a point between the thermostat and the gas-main the pipe L is tapped by the pipe e , which feeds the pilot-burner, and both pipes d and e are provided with suitable cut-off cocks, as shown.
- 30 To the main hot-water pipe H' is connected a short pipe M , which communicates with the valve-chamber m , which is provided with a seat m' (see Fig. 5) for a valve m^2 . A pipe M' leads from valve-chamber m to the sewer or to any other desired point to discharge its contents. The valve m^2 is secured at the end of a rod m^3 , which passes through a stuffing-box m^4 and enters a valve-chamber N through a stuffing-box n' and carries on its lower end a valve n^2 , which is adapted to fit the seat n^3 , formed in said chamber N . The rod m^3 is threaded, and a tapped collar m^5 is run thereon in order to adjust the tension of the spring O , arranged on said rod between the collar and the chamber N . The collar m^5 is formed with a series of holes or openings m^6 in its circumference in order to provide for the application of a spanner-wrench or other tool to adjust the collar on the rod.
- 45 50 To one side of the chamber N a pipe P is connected, which connects with the feed-pipe P' , which enters the lower manifold or drum C through the base of the boiler, while a pipe P^2 leads from the bottom of the chamber N to the water-main.
- 55 From the main hot-water pipe H' a pipe R leads to a closed expansion-chamber R' , provided with a petcock R^3 and arranged above the top of the boiler, which chamber is also in communication with the hot-water pipe G by means of a connecting-pipe R^2 . The expansion-chamber is provided with a valve R^4 .

S is the return-pipe from the radiator I ,

which connects with the feed-pipe P' and also with the waste or discharge pipe M' , the latter connection being made by a pipe S^2 , having a cock S^3 .

In operation the water is admitted to the boiler through pipe P^2 and its connections. The water rises in the boiler and enters expansion-chamber R' when the boiler is filled. By opening cock R^3 on the expansion-chamber before turning on the water the water will escape through said cock, thus indicating when boiler is supplied or filled. The entrance of the water expels the air from boiler into expansion-chamber through pipe R^2 and also through pipe R into said chamber, from which it escapes through valve R^4 . The boiler being filled the gas is permitted to enter through pipe L , and the pilot-burner is ignited, which in turn ignites burner c . The heated gases pass upwardly from the burner c and coming in contact with the coils of tubing heat the water contained therein, which then circulates to the radiator through pipes G and H' and back to the boiler through pipe S . Should steam be generated or the temperature of the water be made too great, the gas-supply is automatically reduced or cut off entirely by the expansion of spring K overcoming the resistance of spring K^5 , and thus moving the rod k , so as to close or partly close the valve k^2 , which controls the gas-supply. Should the movement of valve k^2 cut off the gas entirely, thus cutting off supply from burner c , the latter will be ignited by the pilot-burner, which is burning at all times, as soon as the water cools down sufficiently to permit of the spring K contracting, and thus permitting spring k^5 to expand and move rod k , so as to open valve k^2 and permit the flow of gas to pipe d .

In order to prevent the possibility of an explosion and to relieve the boiler of undue pressure in the event of steam forming therein, I provide the automatic safety device shown in Fig. 5 and which also automatically controls the supply of water to the boiler after the system is once started in operation.

In the event of steam forming in the boiler or the water becoming unduly heated it rises in the expansion-chamber and may escape therefrom through valve R^4 and also from the main hot-water pipe H' through valve-chamber m , from which it escapes to the waste-pipe M' . The pressure on valve m' forces its rod m^3 downwardly, and thus opens valve n^2 and permits a flow of cold water to enter the boiler to replace that escaping through valve m^2 . Thus there being no escape of the water from the boiler excepting through valve-chamber m and the valve in the latter controlling the inlet-valve for the cold water and both valves moving in unison it is obvious that the boiler will be automatically kept supplied with water. The air

valve R⁴ is opened when the boiler is started and kept open until steam issues therefrom, after which it is closed.

It is not intended that water shall reach the top of expansion-chamber when the system is cold.

I make no claim for the peculiar features of the boiler hereinbefore described in this application, but reserve the same for a new application for Letters Patent thereon.

Having thus described my invention, what I claim as new, and desire to secure by Letters Patent, is—

1. In a heating system, a boiler, a main hot-water pipe and a return-pipe connected with said boiler, a feed-pipe, a waste-pipe, and a steam-operated safety device connecting the main hot-water pipe and the waste-pipe and controlling the supply of cold water to the boiler during its operation.

2. In a heating system a boiler, a feed-pipe, a main hot-water pipe leading to the radiator, a waste-pipe, and a safety device arranged between the feed and waste pipes and

connected to the hot-water pipe, said device comprising two valves adapted to be operated in unison to control the flow of water to the feed-pipe and the flow from the waste or discharge pipe.

3. In a heating system, a boiler, an expansion-chamber connected therewith, a main hot-water pipe leading to the radiator, a return-pipe from the radiator to the boiler, a waste-pipe from said hot-water pipe, a feed-pipe, a burner connected with the gas-supply, thermostat arranged in the hot-water pipe and controlling the flow of gas to the burner, a safety device arranged between the hot-water pipe and the feed-pipe and controlling the inlet of water to the boiler and the outflow from the hot-water pipe, and a pilot-burner connected to the gas-supply.

In testimony whereof I affix my signature in presence of two witnesses.

WILLIAM J. SHEETZ.
